CHARLES F. STODDARD, OF NEW YORK, N. Y., ASSIGNOR TO AMERICAN PIANO COMPANY, OF NEW YORK, N. Y., A CORPORATION OF NEW JERSEY.

EXPRESSION MECHANISM FOR AUTOMATIC MUSICAL INSTRUMENTS.

1,409,486.

Specification of Letters Patent. Patented Mar. 14, 1922.

Application filed September 24, 1914, Serial No. 863,359. Renewed October 25, 1920. Serial No. 419,492.

To all whom it may concern:

Be it known that I, CHARLES F. STODDARD, a citizen of the United States, and a resident of New York, in the county of New York and State of New York, have invented an Improvement in Expression Mechanism for Automatic Musical Instruments, of which the following description, in connection with the accompanying drawings, is a specification, like characters on the drawings representing like parts.

This invention relates to apparatus for automatically varying playing intensities in automatic musical instruments, such, for instance, as player-pianos and the like.

Among other objects, the invention is intended to provide apparatus capable of producing prompt changes in playing intensity while maintaining intensities so far as may be desired, regardless of the number of tones sounded.

The character of the invention may be readily understood by reference to the accompanying drawing, which shows diagrammatically one illustrative embodiment.

In the drawings, a bellows 1 exemplifies a source of power for operating the striker pneumatics which may be operated selectively, as well understood by those skilled in the art, from a tracker board through ducts 3. A passage 4 connects the action chests 5 of the player actions with a port 6 into a regulating bellows 7 having a regulator valve 8 controlling a port 9 communicating with the source of power 1. As well understood in the art, the valve 8 regulates the flow of air from the action chest 5 to the source 1.

The regulator valve 8 is connected by a link 10 with the movable board of the regulator bellows 7.

The regulator is provided with a spring 11 pivoted at its upper end to a stationary bracket 12. The lower end of the spring 11 carries a roller 13 to engage a bracket 14 mounted upon the movable board of the regulator 7. The spring 11 is swung upon its pivot 12 to move the roller 13 along the track 14 to vary the leverage of the spring on the regulator bellows; and the track 14 is preferably curved so that its parts shall be substantially equidistant from the pivot 12 of the spring. As the spring 11 is moved counterclockwise from the position shown in the drawing, the roller 13,—constituting the point of application to the bellows 7 of the

pull of the spring,—moves nearer the hinge of the bellows which constitutes the fulcrum of the lever upon which the spring acts. Accordingly, the leverage favorable to the pull of the spring diminishes, thereby diminishing the effective pull upon the movable board of the regulating bellows. The lower part of the spring 11 passes through an eye-piece 16 fastened to the movable board of an expression bellows 18 so that as said bellows 18 is collapsed and expanded, the eye-piece 16 will cause the spring 11 to accompany the movement of said movable board. The pneumatic 18 is arranged to be exhausted through a duct 20 preferably having an adjustable bleed by which the capacity of the duct may be diminished so as to cause the pneumatic 18 to collapse slowly and thereby slowly and gradually move the spring 11 toward the right in the drawing to reduce with a correspondingly slower speed the effective leverage of the spring 11 upon the regulator bellows 7. The effect of this, as will be readily understood by those skilled in the art, is to modify the regulation so as to produce a gradual slow diminuendo. When atmosphere is admitted through the duct 20, the bellows 18 having been wholly or partially collapsed, is then expanded by a spring 22 connected to the eye-piece 16. This returns the spring 11 to or toward the position shown in the drawing and thereby produces a slow crescendo.

The bellows 18 may also be exhausted through a duct 25 of greater capacity than the duct 20 to collapse the bellows 18 at a greater speed, but preferably the duct 25 is of such restricted capacity as to collapse the pneumatic 18 to give a diminuendo effect similar to, but faster than, that produced by exhausting through the duct 20. When atmosphere is re-admitted through the duct 25, a fast crescendo results.

The pneumatic 18 may also be exhausted through a duct 27 of sufficiently large capacity to permit the pneumatic to be exhausted practically instantaneously to move the spring 11 very rapidly toward the right in the drawing to produce a distinct step of reduction in playing intensities. When atmosphere is re-admitted through the large capacity duct 27, the bellows 18 is expanded practically instantaneously to produce a distinct step of increase in playing intensities.

To provide for a plurality of distinct

steps, means are provided for arresting the collapse of the pneumatic 18 at different stages. Pivoted at 30 to the movable board of the pneumatic 18 is a rod 31 arranged 5 to slide endwise through a stationary eye-bracket 32. This rod 31 is arranged to contact at its end under different circumstances, with stop devices next described.

A pneumatic 35 arranged to be exhausted 10 through a duct 36 is provided with a stop 37 arranged to be positioned in the path of movement of the end of the rod 31 and to arrest movement thereof when the pneumatic 18 is collapsed through say one-third 15 of its total collapsing movement.

A pneumatic 40 arranged to be exhausted through a duct 41 has a stop 42 arranged to be positioned in the path of movement of the rod 31 and to arrest the movement of 20 said rod when the pneumatic 18 has collapsed through, say two-thirds of its movement.

When neither of the stops 37 nor 42 is interposed in the path of movement of the rod 31 in collapse of the pneumatic 18, the latter is completely collapsed until the end of the rod 18 strikes a stationary stop surface 45.

Having been thus collapsed, if atmosphere is admitted to the pneumatic 18, to start an 30 expanding movement, the stop 42 may be interposed in the returning path of the head 46 on the rod 31 (the stop 42 being forked to straddle the shank of the rod 31) so as to arrest the expanding movement of the rod 31 at the end of substantially one-third 35 thereof. Similarly, in the further expanding movement of the rod 31 the stop 37 (which is also forked) may be interposed in the path of the head 46 to arrest its movement at the end of substantially the second-third 40 thereof. If neither of the stops 37 or 42 be interposed in the returning path of the head 46, the pneumatic 18 is permitted its full expanding movement until the head 46 is arrested by a stop 48.

The pneumatic 18 may thus be collapsed at any one of several speeds and to three different extents, to produce corresponding reductions in playing intensities; and likewise the pneumatic 18 may be expanded at any one of a plurality of speeds and through three extents to produce corresponding increases in playing intensity. The decreases and increases in playing intensity may be 50 by way of diminuendo and crescendo at different speeds or may be practically instantaneous distinct steps. All the effects described are produced in the illustrative apparatus by varying the effective leverage of the regulating spring upon the regulator bellows and thereby modifying the regulation so as to produce a change in the action of the regulator upon the valve 8.

The various ducts 20, 25, 27, 36 and 41, may 65 be open to atmosphere or a source of exhaust

in any practicable manner as by means of primary, or primary and secondary, valves such as are used in connection with the usual tracker ducts leading to tone-sounding actions such as the playing pneumatic 2.

It is to be understood that this invention is not limited to the particular construction, organization and mode of operation shown in the drawings and described in illustration. On the contrary, the invention may be variously embodied and the particular construction may be variously modified within the scope of the subjoined claims. It is not indispensable that all the features of the invention be used conjointly since, in some 75 instances, they may be used separately to advantage.

Claims.

1. In a musical instrument, the combination of playing pneumatics; a source of power for operating the playing pneumatics; a regulating pneumatic having a valve between said source of power and the playing pneumatics; a regulator spring connected to the regulating pneumatic; means for varying the effective leverage of said spring upon said pneumatic; and pneumatic means to operate said varying means.

2. In a musical instrument, the combination of playing pneumatics; a source of power for operating the playing pneumatics; a regulating pneumatic having a valve between said source of power and said playing pneumatics; a spring connected to said regulating pneumatic; an expression pneumatic; and means for reducing the effective action of the spring upon the regulating pneumatic by collapse of said expression bellows.

3. In a musical instrument, the combination of playing pneumatics; a source of power for operating the playing pneumatics; a regulator having a valve between said source of power and the playing pneumatics; an expression pneumatic acting upon the regulator for modifying the action thereof to produce changes in playing intensities; means for exhausting and expanding the expression pneumatic; and means for limiting both collapsing and expanding movement 110 of said expression pneumatic in a plurality of steps.

4. In a musical instrument, the combination of playing pneumatics; a source of power for operating the playing pneumatics; a regulator having a valve between said source of power and said playing pneumatics; a regulator spring; and pneumatically actuated means for shifting the point of application of the force of said spring 125 to the regulator, gradually to produce a crescendo.

5. In a musical instrument, the combination of playing pneumatics; a source of power for operating the playing pneumati- 130

- ics; a regulator having a valve between said source of power and said playing pneumatics; a regulator spring; and pneumatically actuated means to shift the point of application of the force of said spring to the regulator, abruptly to produce a distinct step of change in playing intensity.
- 5 6. In a musical instrument, the combination of playing pneumatics; a source of power for operating the playing pneumatics; a regulator having a valve between said source of power and said playing pneumatics; a regulator spring; pneumatically actuated means to shift the point of application of the force of said spring to the pneumatic gradually at different speeds to produce crescendos at different speeds.
- 10 7. In a musical instrument, the combination of playing pneumatics; a source of power for operating the playing pneumatics; a regulator having a valve between said source of power and said playing pneumatics; a regulator spring; pneumatically actuated means to shift the point of application of the force of said spring to the regulator; and means to determine different distances through which said point of application may be shifted.
- 15 8. In a musical instrument the combination of playing pneumatics; a source of power for operating the playing pneumatics; expression governing means interposed between the source of power and the playing pneumatics including a spring acting upon
- a regulator pneumatic; means to vary the effective leverage of the spring; and pneumatic means to operate said varying means.
9. In a musical instrument the combination of playing pneumatics; a source of power for operating the playing pneumatics; expression governing means interposed between the source of power and the playing pneumatics including a pneumatic having a pivoted movable board and a spring connected thereto; means whereby the spring may be connected to the movable board of the pneumatic at different distances from the pivot; and pneumatic means to change the point of connection of said spring to said movable board.
- 40 10. In a musical instrument the combination of playing pneumatics and a source of power for operating them, a regulating pneumatic having a valve to control the flow of air from the player pneumatics to the source of power, an expression pneumatic for varying playing intensities, and means operated by the expansion of said expression pneumatic to increase playing intensities and by the collapse of said expression pneumatic to reduce playing intensities.
- 45 50
- In testimony whereof, I have signed my name to this specification, in the presence of two subscribing witnesses.
